UNITED STATES PATENT OFFICE.

OTTO MARKLEIN, OF BROOKLYN, NEW YORK, ASSIGNOR TO WILLIAM OSCAR SHADBOLT, OF NEW YORK, N. Y.

TAIL-GATE FOR VEHICLES.

1,390,999.

Specification of Letters Patent. Patented Sept. 20, 1921.

Application filed February 15, 1921. Serial No. 445,068.

To all whom it may concern:

Be it known that I, Otto MARKLEIN, a citizen of the United States, and a resident of the borough of Brooklyn, in the city and State of New York, have invented certain new and useful Improvements in Tail-Gates for Vehicles, of which the following is a specification.

My invention relates to devices commonly known as tail gates or tail boards which are commonly used at the rear ends of commercial vehicles, being pivotally attached thereto, so as to be opened for the removal of the load or closed and secured for the purpose 15 of retaining the load.

The object of the invention is to provide a tail gate for a truck or other commercial vehicle, which shall be simple, strong and efficient, and which shall be capable of either 20 swinging out upon its lower edge into a plane approximately the same as that of the floor of the vehicle so as to serve as an extension of the same and permit the removal of the load thereover, or to swing outward 25 upon a pivotal line located substantially above its lower edge so as to permit the automatic discharge of the load under the tail gate, as is often desired in some forms of dumping vehicles.

30 The invention consists in the novel construction, arrangement and combination of various elements and parts as hereinafter fully described and as shown in the accompanying drawings.

35 In the said drawings, Figure 1 is an elevation of a tail gate constructed according to my invention, showing the same adapted to swing upon its lower edge, as first above mentioned; Fig. 2 is a similar view, showing 40 the tail gate adapted to swing open on a line located somewhat above its middle; Fig. 3 is a side view of a portion of a truck provided with my improved tail gate, showing the position of the parts as indicated in Fig. 1; 45 and Fig. 4 is a view similar to Fig. 3, but showing the arrangement of the parts similar to that indicated in Fig. 2.

In carrying my invention into effect, in the embodiment thereof which I have selected for description in this specification and illustration in the accompanying drawings, I provide a carrying body, the rear portion only of which is shown, which may be supported upon a suitable substructure.

adapted to be mounted upon the running gear of the vehicle. The sides of the body are designated 5 (see Figs. 3 and 4). The floor of the body is designated 6. The tail gate or tail board is designated 7. At each end of the tail gate, that is, at each side of the vehicle, are bolted a pair of angle-irons 8, forming between them a groove 9 (see Figs. 1 and 2). To the floor of the body, and extending rearwardly therefrom, are eyes 10, each being the end of one of the leaves of hinges upon which the tail gate swings when it is in the position shown in Figs. 1 and 3. The other leaves, for the two intermediate hinges, are formed by the members 11 bolted on to the tail gate (see 70 particularly Fig. 1), each of which members 11 is provided with an eye similar to the eyes 10, and the hinges are completed by the insertion of pintles 12 which are preferably secured by a cotter-pin as shown. 75 For the two exterior hinges—the pair at the extreme ends of the tail gate—the other leaves are formed by members 13, which are provided with eyes at each end. When the tail gate is in the position shown in Figs. 1 and 3, pintles 12 are inserted through the eyes in one end of the members 13 and through the eyes 10 attached to the tail gate, and pintles 14 through the eyes in the other 85 ends of the members 13 and through perforations in the angle-irons 8. Under this arrangement, the tail gate is adapted to swing downward upon its lower edge into a plane approximately the same as that of the floor of the carrying body, being prevented 90 from falling lower by the chain 15. The tail gate is secured in its closed position by swinging the link 35 into engagement with the eye 36.

When it is desired to arrange the tail gate 95 so that it may swing open from above so as to permit the discharge of the load underneath the tail gate when the carrying body is tilted, that is, according to the arrangement shown in Figs. 2 and 4, the pintles 12 are 100 removed from the hinges at the lower corners of the tail gate, formed by the eyes 10 and the lower ends of the swinging member 13, and the said swinging members are swung upward into the position shown in Figs. 2 and 4 and are there pivotally secured to devices attached to the rear ends of the sides of the carrying body. In the form of the body

shown in the drawings, an extra or additional side board 19 (one on each side) is provided, to which are secured a series of downwardly extending tongues 20, the lower ends of which are held in sockets 21 as shown in Figs. 3 and 4. The rear ends of these additional side boards 19 are protected by plates 22 and to these and to the side boards are secured members 23 each of which has a 10 pair of outwardly projecting perforated ears 24, between which the upper ends of the members 13 lie when said members are swung into their upward position as shown in Figs. 2 and 4 and the pintles 12 are then 15 inserted through said perforations in said ears and through the eyes in the ends of the swinging arms 13. The pintles 12 are then removed from the intermediate hinges at the bottom of the tail gate and, as will be readily 20 seen, the tail gate is then in a condition to be swung outward at the bottom, permitting the dumping of the load when the carrying body is tilted. In order to prevent the tail gate from swinging merely on the pintles 25 14, which it might tend to do, and cause it and the swinging members 13 to swing from their pivotal suspension at their upper ends, I provide pins 30 adapted to pass through 30 perforations in the angle-irons 8 and the swinging members 13 and cause same to swing together.

Latches 16 pivoted at 17 to the sides of the carrying body are provided, each of which is adapted to engage with a stop 18 35 on the tail gate; this latch and stop serve to hold the tail gate closed, more particularly in the arrangement shown in Figs. 2 and 4, the link 35 serving for this purpose more particularly in the arrangement shown in 40 Figs. 1 and 3. When it is desired to release the tail gate and allow the same to open, whether it is arranged as shown in Figs. 1 and 3 so as to open at the top or as shown in Figs. 2 and 4 so as to open at the bottom, 45 the latch 16 is raised into the position shown by the dotted lines in Fig. 4, thus disengaging the same from the stop 18, and the link 35 is freed from the eye 36, thus leaving the tail gate free to open.

50 The operation of my invention is as follows: It will be obvious that a vehicle provided with a tail gate constructed according to my invention is adapted to be used either as an ordinary truck in which the tail board 55 is attached at the bottom, and the top is swung down into an approximately horizontal position and the load removed over the same; or as a dumping truck, in which the body is tilted to discharge the 60 load, in which case the tail gate swings outward from above and permits the load to escape underneath the same. The first use

of the tail gate is shown in Figs. 1 and 3, and the second use in Figs. 2 and 4.

The advantages of my invention will be 65 obvious from what has been above said with regard to its construction and mode of operation.

Having thus described my invention, what I claim as new and desire to secure by Let- 70 ters Patent is as follows:

1. The combination with a vehicle carrying body; of a tail gate therefor and means adapted to pivotally secure said tail gate to said body: said means comprising swinging arms adapted to be pivotally attached at one end to said tail gate at a point above the lower edge thereof and to be pivotally attached at the other end to said carrying body at a point in or near the plane of the 80 floor thereof or to be swung upward and pivotally attached to said body at a point substantially above the carrying floor thereof. 75

2. The combination with a vehicle carrying body; of a tail gate therefor and means adapted to pivotally secure said tail gate to said body: said means comprising swinging arms adapted to be pivotally attached at one end to said tail gate at a point above the lower edge thereof and to be pivotally attached at the other end to said carrying body at a point in or near the plane of the 90 floor thereof or to be swung upward and pivotally attached to said body at a point substantially above the carrying floor thereof. 85

100

3. The combination with a vehicle carrying body; of a tail gate therefor and means adapted to pivotally secure said tail gate to said body: said means comprising swinging arms adapted to be pivotally attached at one 105 end to said tail gate at a point above the lower edge thereof and to be pivotally attached at the other end to said carrying body at a point in or near the plane of the floor thereof or to be swung upward and pivotally attached to said body at a point substantially above the carrying floor thereof. 110
